tion of Delaware

Application June 30, 1936, Serial No. 88,073

9 Claims. (Cl. 250—33)

This invention relates broadly to high frequency signalling systems, and more particularly to arrangements for antenna transmission lines over which it is desired to operate a plurality of transmitters of different frequencies for simultaneously feeding the same antenna.

One of the objects of the invention is to enable two or more transmitters of different frequencies to feed the same transmission line over 10 different branch circuits in such manner that each branch has negligible effect on the flow of energy from the other branch or branches toward the common load circuit. This object is achieved first by shunting each branch at a predetermined 15 location with a circuit of predetermined electrical constants, whereby the branch enables the unrestricted flow of energy thereover from its associated transmitter toward the common antenna system, and the shunt circuit provides an effective 20 short circuit for energy from any other branch, and secondly, by making each branch appear at the point of junction to the common transmission line as a circuit of extremely high impedance to the flow of energy from any other branch.

Another object is to enable matching the characteristic impedance of the main transmission line for all transmitter frequencies used to simultaneously excite the load.

The invention has been found to be especially 30 useful in the broadcasting of television signals wherein both voice and video transmitters of different frequencies are used to feed simultaneously the same antenna.

A better understanding of the invention may be had by referring to the following description and accompanying drawings, in which Figs. 1 to 5 illustrate different embodiments of the invention, and Fig. 6 illustrates impedance curves showing 40 the manner in which the shunt elements of Fig. 5 function.

Fig. 1 schematically illustrates a simple case embodying the principles of the invention wherein two transmitters T_1 and T_2 , respectively generating waves whose lengths are λ_1 and λ_2 , the wavelength of λ_2 being chosen exactly twice that of λ_1 , feed the same antenna A over a common transmission line TL. Transmitter T_1 feeds line TL over a branch circuit comprising lines b_1 and c_1 , and transmitter T_2 feeds line TL over another branch circuit comprising lines b_2 and c_2 , both lines c_1 and c_2 joining the common line TL at the junction points J. Antenna A comprises two coaxially arranged arms, each of which has a length

equal to half the length of the communication wave λ_1 , i. e.,

$\frac{\lambda_1}{2}$

or one-quarter the length of the longer communication wave λ_2 .

In other words, antenna A is a double half-wave dipole at the higher frequency corresponding to the shorter wavelength λ_1 , and a single half-wave dipole at the lower frequency corresponding to the longer wavelength λ_2 .

For obtaining the desired restrictions in the branch circuits, there is employed at the junction a of lines b_1 and c_1 of one branch circuit, an impedance element d_1 which acts as an open circuit for the flow of energy of the frequency of the wave λ_1 and as a short circuit for the flow of energy of the frequency of the wave λ_2 , but which acts at the junction J as a high impedance to the flow of energy from transmitter T_2 . At the junction b of lines b_2 and c_2 of the other branch circuit, there is employed an impedance element d_2 which acts as an open circuit for the flow of energy of the frequency of the wave λ_2 and as a short circuit for the flow of energy of the frequency of the wave λ_1 , but which acts as a high impedance at J to the flow of energy from transmitter T_1 . For this purpose element d_1 is here shown as a straight line which is open at the far end and has a length equal to

$\frac{\lambda_2}{4}$

which is also

$\frac{\lambda_1}{2}$

Element d_2 is here also shown as a straight line and closed or short-circuited at the far end and has a length equal to

$\frac{\lambda_2}{4}$

which is equal to

$\frac{\lambda_1}{2}$

Section c_1 is designed to have a length equal to

$\frac{\lambda_2}{4}$

and section c_2 a length equal to

$\frac{\lambda_1}{4}$

In order to more fully understand the reason

for the particular lengths chosen for the straight line sections d_1 , d_2 and c_1 , c_2 , it should be remembered that a straight section of line a half-wavelength long or a multiple of a half wavelength acts as a line of zero length, whether it is open or short circuited at the far end; and that a quarter wavelength line, or an odd multiple thereof, closed at the far end acts as an open circuit, while a quarter wavelength line or an odd multiple thereof open at the far end acts as a short circuited line. Putting it still another way, a half-wave section of line, short circuited at the far end, acts, for a particular frequency, as a series tuned circuit of lumped inductance and capacity, whereas an open half-wave section of line acts, for a particular frequency, like a parallel tuned circuit of lumped inductance and capacity.

In operation, the energy from transmitter T_1 flows without impediment over lines b_1 and c_1 to the line TL , since element d_1 acts as a very high impedance shunt on the branch line b_1 , c_1 , i. e., infinite impedance or zero loss, for energy from T_1 . However, the closed line or element d_2 acts as a short circuit at the junction b for any energy from T_1 . At junction J , however, which is a quarter of the wavelength of λ_1 from b , the entire branch circuit for T_2 has a very high impedance to the flow of energy from T_1 so that the effect of the branch circuit of T_2 is negligible on the flow of energy from T_1 to the line TL and antenna A .

As for the energy from transmitter T_2 , the element d_2 acts as an open circuit and has negligible effect on the flow of energy from this transmitter to the line TL and antenna A . Because of the length of c_1 , however, the element d_1 will act at a as a short circuit to any energy from transmitter T_2 . At junction J , however, the entire branch circuit of T_1 acts as a high impedance to the flow of energy from T_2 so that the effect of the branch circuit of T_1 is negligible on the flow of energy from T_2 to the antenna.

Fig. 2 shows a more general arrangement wherein the two frequencies of the transmitters T_1 and T_2 have no simple relationship as in the special case of Fig. 1. The circuit of Fig. 2 is similar to Fig. 1 except that instead of the line elements d_1 and d_2 of Fig. 1 there are provided lumped reactance circuits d'_1 and d'_2 , and also provision is made for matching the antenna circuit to the characteristic impedance of the main line TL by means of circuits m and n . It should be noted that circuit d'_2 comprises a series branch of inductance L'_1 and capacity C'_1 shunted by a capacity C_2 , whereas circuit d'_1 comprises a series branch of inductance L_1' and capacity C_1' shunted by an inductance L_2 . The circuit d'_1 acts as a parallel tuned or anti-resonant circuit to energy of the frequency of the wave λ_1 , and as a series tuned or effective short circuit to energy of the frequency of wave λ_2 . This is accomplished by making the reactance values of L_1' and C_1' equal at the frequency of λ_2 . At the same time L_1' and C_1' are so chosen that at the frequency of λ_1 , the series circuit of L_1' and C_1' becomes in effect a capacity reactance equal to the inductive reactance of L_2 .

The following mathematical relations must exist to obtain this result:

$$W_1^2 L_1' C_1' = 1$$

$$W_2^2 L_2 C_1' = 1 - W_1^2 L_1' C_1'$$

75 where $W_1 = 2\pi f_1$ and $W_2 = 2\pi f_2$, the frequencies

f_1 and f_2 , respectively corresponding to the transmitter wavelengths λ_1 and λ_2 , it being understood that λ_1 is shorter than λ_2 from which it follows that W_1 is greater than W_2 .

Similarly the circuit d'_2 is designed to act as a parallel tuned or anti-resonant circuit for frequency f_2 and as a series tuned or short circuit for frequency f_1 . To obtain this result the following relations must exist:

$$W_2^2 L'_1 C'_1 = 1$$

$$\frac{C'_1}{C_2} = W_1^2 L'_1 C'_1 - 1$$

It should be observed in passing, that the circuit d'_1 across the branch through which the higher frequency f_1 flows must provide a shunt inductance to its series tuned circuit, whereas the circuit d'_2 across the lower frequency branch must provide a shunt capacity to its series tuned circuit.

For matching the impedance of the antenna system to the characteristic impedance of line TL , for the different frequencies of transmitters T_1 and T_2 , there may be employed circuits m and n which may take the form of lumped reactances, or straight line sections, as shown in Figs. 3 and 4. The broad principles underlying the manner of matching the impedance of the antenna system is described in my copending application Serial No. 31,756, filed July 17, 1935, to which reference is made for a detailed description thereof.

Fig. 3 illustrates schematically a system like that of Fig. 2, wherein any relationship of frequencies for the transmitters can be used. Here again it is assumed that the wavelength of transmitter T_1 is shorter than that of T_2 . The impedance elements d_3 and d_4 in this figure are sections of transmission lines rather than lumped reactances and are connected to the branch circuits at points intermediate their ends. It should be noted that the distance from one open end of d_3 to its point of connection to the branch circuit of T_1 is one-quarter of the wavelength of λ_2 , while the distance from the free end of d_4 to the point of connection to the branch circuit of T_2 is one-quarter of the wavelength of λ_1 . The length of c_1 and c_2 from J to the junction points of the impedance elements are here again one-quarter of the length of the communication wave emanating from the other branch circuit. An analysis of Fig. 3 will show that each branch acts as a high impedance at J for the flow of energy from the other branch toward the antenna and consequently has negligible effect thereon, and the elements d_3 and d_4 act like open and short circuits to the different frequencies in precisely the same manner hereinabove mentioned in connection with the elements d'_1 and d'_2 of Fig. 2.

With certain frequency relationships of f_1 and f_2 , it may be desirable to use odd multiples of the quarter wavelengths shown in Fig. 3, rather than a simple quarter wavelength. Similarly, in certain instances we may wish to use any multiple of a half wave for the half wavelengths appearing in the drawings. In a practical application of the invention where losses must be considered, such as may be the case where the frequencies f_1 and f_2 are close to one another, it may be necessary to use the above mentioned multiples of the lengths shown in the drawings in order to obtain the desired frequency accepting and rejecting actions of the elements.

The system of Fig. 3 is not limited to the case

where the line sections d_3 and d_4 are either open at both ends or at one end only, since it is feasible to use in certain cases, instead of d_3 and/or d_4 , a line section closed at both ends. In other words, any type of line section may be used which satisfies the requirement of being in effect an open circuit at one frequency and a short circuit at the other frequency. The following formulas show the reactances for the three different types 10 of line sections which may be used:

1. Line section closed at both ends:

$$\text{Reactance } X = \frac{Z_0}{2} [\sin 2S - \cot L(1 - \cos 2S)]$$

15 where S is the distance angle from either end.

2. Line section open at both ends:

$$X = \frac{-Z_0}{2} [\sin 2S + \cot L(1 + \cos 2S)]$$

20 where S is the distance angle from either end.

3. Line section open at one end and closed at the other end (U section).

$$25 X = \frac{Z_0}{2} [\sin 2S + \tan L(1 - \cos 2S)]$$

where S = the distance angle from the closed end, where Z_0 is the surge impedance of the line section 30 and L is the total length of the line section expressed as an angle.

The distance angle S in the above formulas equals

$$\frac{360^\circ \times \text{distance}}{\text{wavelength}}$$

35 The above formulas for the reactance of the line sections take no account of losses, and where it is desired to take account of losses, hyperbolic functions should be substituted for the circular functions after substituting the complex line angle consisting of the attenuation and phase constants in place of the simple angular lengths above, according to well known transmission line theory.

40 Impedance matching of the antenna system and line TL for the two frequencies of T_1 and T_2 is obtained by elements m' and n' in the manner described in my copending application Serial No. 31,756, supra.

45 Fig. 4 shows a system wherein three transmitters T_1 , T_2 and T_3 of different frequencies are employed, according to the invention, to excite simultaneously the same transmission line TL and the antenna. The principles involved in the construction of Fig. 4 are the same as those of Fig. 3 with the exception that each of the shunt circuits d_5 , d_6 and d_7 are so designed as to result in very high impedance for the frequency of the transmitter associated with the same branch and an effective short circuit for the other two frequencies of the other transmitters. It is assumed in this case that the wavelength λ_1 generated by T_1 is shorter than the wave λ_2 generated by T_2 , in turn, shorter than the wave λ_3 generated by T_3 . Each of the three shunt circuits d_5 , d_6 and d_7 has three branches. Circuit d_5 is here shown consisting of two branches whose lengths l_1 and l_2 are each closed at one end, and a third branch whose length l_3 is open. Circuit d_6 has only one branch l_1 closed and the other two branches l_2 and l_3 open. Circuit d_7 has all three of its branches l_1 , l_2 and l_3 open. The lengths of the branches for each of the shunt circuits d_5 , d_6 and d_7 shown in the drawings are

determined by the following mathematical relations:

For circuit "d₅"

$$\begin{aligned} \cot m_1 l_1 + \cot m_1 l_2 - \tan m_1 l_3 &= 0 \\ \cot m_2 l_1 + \cot m_2 l_2 - \tan m_2 l_3 &= \pm \infty \\ \cot m_3 l_1 + \cot m_3 l_2 - \tan m_3 l_3 &= \pm \infty \end{aligned}$$

For circuit "d₆"

$$\begin{aligned} \cot m_1 l_1 - \tan m_1 l_2 - \tan m_1 l_3 &= \pm \infty \\ \cot m_2 l_1 - \tan m_2 l_2 - \tan m_2 l_3 &= 0 \\ \cot m_3 l_1 - \tan m_3 l_2 - \tan m_3 l_3 &= \pm \infty \end{aligned}$$

For circuit "d₇"

$$\begin{aligned} \tan m_1 l_1 + \tan m_1 l_2 + \tan m_1 l_3 &= \pm \infty \\ \tan m_2 l_1 + \tan m_2 l_2 + \tan m_2 l_3 &= \pm \infty \\ \tan m_3 l_1 + \tan m_3 l_2 + \tan m_3 l_3 &= 0 \end{aligned}$$

The invention, it is to be understood, is not limited to the particular circuits d_5 , d_6 and d_7 shown with their types of open and closed branches, since other combinations of line sections, or lumped reactance circuits, may be used, provided the essential requirement of having a high impedance at one frequency and a very low impedance at the other two frequencies be satisfied.

20 Where impedance matching of the line TL is desired, we may employ circuits m'_1 , n'_1 and o . The manner in which the values and locations of m'_1 and n'_1 is determined is described in my copending application Serial No. 31,756, supra. Circuit o also employs the same principles shown in my copending application and shows another embodiment wherein three branches are used in order to obtain a certain finite value of reactance at the third frequency and at the same time a very high reactance at the other two frequencies.

25 The lengths of the branches of the matching circuits m'_1 , n'_1 and o are determined from the following relations, it being understood that the locations of these circuits and the values of the 30 reactances x_1 , x_2 and x_3 may be obtained from the procedure outlined in my copending case.

For circuit "n'_1"

$$Z_0 \tan m_1 l_1 = X_1$$

For circuit "m'_1"

$$\begin{aligned} \cot m_1 l_1 - \tan m_1 l_2 &= 0 \\ \cot m_2 l_1 - \tan m_2 l_2 &= \frac{Z_0}{X_2} \end{aligned}$$

For circuit "o"

$$\begin{aligned} \cot m_1 l_1 - \tan m_1 l_2 - \tan m_1 l_3 &= 0 \\ \cot m_2 l_1 - \tan m_2 l_2 - \tan m_2 l_3 &= 0 \\ \cot m_3 l_1 - \tan m_3 l_2 - \tan m_3 l_3 &= \frac{Z_0}{X_3} \end{aligned}$$

55 Fig. 5 shows one application of the invention to a television system wherein it is desired to use bands of both video and voice frequencies simultaneously over the same antenna, and wherein 60 the video and voice frequencies are relatively close to each other. It should be noted that in this instance concentric lines are shown, although it will be obvious that two wire lines may just as well be used.

65 In Fig. 5 the voice transmitter (λ_1) has a carrier frequency of 52 megacycles and a very small band between 51.98 and 52.02 megacycles, whereas the video transmitter (λ_2) has a carrier frequency of 49.75 megacycles and a very wide band between 48.25 and 51.25 megacycles. The shunt element g across the voice transmitter branch is here designed to give a high impedance to the small band of frequencies emanating from the 70 75

voice transmitter, and to provide a very low impedance at the junction *a* over the very wide band of video frequencies. Similarly, the shunt circuit *k*, *r* is designed to give a high impedance to the wide band of video frequencies and to provide a very low impedance at the junction *b* for the small band of voice frequencies. At the junction *J* each branch has negligible effect on the other branch since each branch acts as a high impedance at this junction to the frequencies coming from the other branch.

A circuit *g*, in this particular instance where it is essential that losses be taken into account, gives a very high impedance over a relatively narrow band of frequencies and a quite low impedance over a band of considerable width. This type of shunt line section circuit is very satisfactory for the small voice frequency range of the voice transmitter. For the video branch we require just the reverse, that is, a shunt circuit which will give a very high impedance over a very wide frequency band and a quite low impedance over a relatively narrow frequency band. This is obtained in Fig. 5 by providing circuit *r* which has the same dimensions as circuit *g* and connecting through a quarter wave section *K*. In this case we may say that *K* acts as an impedance inverter.

The reason why the shunt line section open at both ends, of the type shown in Fig. 3, was not used at the junction *b* in Fig. 5 is because such an open line section provides a high impedance over a small range of frequencies and low impedance over a wide band of frequencies, whereas the opposite effect is required in the case of Fig. 5.

Fig. 6 shows the general shape of the impedance curve for the shunt line sections *g* and *k*, *r*. It will be seen that the curve for *g* shows a relatively low impedance over the video frequency band and a high impedance over the voice frequency band, whereas the curve for *k*, *r* shows a relatively high impedance over the video frequency band and a low impedance over the voice frequency band.

In practice it will be found that some current from one branch will find its way into the other branch but the degree of such undesired feedback depends principally upon the efficiency of the shunt sections across the branches. A very high degree of freedom from undesired feedback may be obtained by using concentric branch lines of relatively large diameter.

The invention, it will be understood, is not limited to the precise arrangements of parts shown since various modifications may be made without departing from the spirit and scope thereof. For example, although two conductor lines have been shown in all the figures of the drawings, the principles and formulas of the invention apply equally well to single conductor lines with ground return.

What is claimed is:

1. In combination, a first source of high frequency energy of wavelength λ , a second source of high frequency energy of wavelength 2λ , a main line and a load connected to said main line, a first two-conductor line connecting said first source to said main line, a second two-conductor line connecting said second source to said main line, a first shunt circuit connected across said first two-conductor line at a distance from the junction of said first line with the main line equal to one-quarter of the length of the wave 2λ , said first shunt circuit comprising a two-conductor

line section whose length is equal to one-quarter of the length of the wave 2λ , the ends of said line section being open, a second shunt circuit connected across said second two-conductor line at a distance from the junction of said second line with the main line equal to one-quarter of the length of the wave λ , said second shunt circuit comprising a two-conductor line section whose length is equal to one-quarter of the length of the wave 2λ , said last shunt circuit being closed at its end farthest removed from its point of connection, whereby each shunt circuit presents, at its point of connection across its two-conductor line, high impedance to the flow of energy of the frequency of the source directly associated with said line, and a low impedance to the flow of energy of the other source, and each two-conductor line presents a high impedance at the point of junction to said main line to the flow of energy coming from the other two-conductor line.

2. In combination, a first source of high frequency energy of wavelength λ_1 , a second source of high frequency energy of longer wavelength λ_2 , a main line and a load connected to said main line, a first two-conductor line connecting said first source to said main line, a second two-conductor line connecting said second source to said main line, a first shunt circuit comprising a line section connected across said first two-conductor line at a point located from the junction of said first line with the main line a distance equal to

$$\frac{\lambda_2}{4}$$

said shunt circuit being open-ended and having an overall length equal to

$$\frac{\lambda_1}{2}$$

the distance from one open end of said first shunt circuit to its point of connection across said first two-conductor line being

$$\frac{\lambda_2}{4}$$

a second shunt circuit also comprising a line section connected across said second two-conductor line at a point located from the junction of said second line with the main line a distance equal to

$$\frac{\lambda_1}{4}$$

said last line section being closed at only one end and having an overall length equal to

$$\frac{\lambda_2}{4}$$

the distance from the open end of said last line section to its point of connection across said second two-conductor line being

$$\frac{\lambda_1}{4}$$

and a pair of line sections connected to different points on said main line for matching the load to the characteristic impedance of the main line for the different frequencies of said two sources.

3. In combination, a first transmitter of one frequency, a second transmitter of another frequency, a main transmission line, an antenna connected to said main line, a two-conductor line connecting each transmitter to said transmission line, and an impedance circuit in shunt across each of said two-conductor lines, each of said impedance circuits being constructed and arranged to provide at its point of connection to its

two-conductor line, a high impedance to the flow of energy in its associated two-conductor line of the frequency of its associated transmitter and a low impedance to the flow of energy in its associated line of the frequency of the other transmitter, the shunt impedance circuit across one two-conductor line being located from the junction of said one two-conductor line with the main transmission line a distance equal to an odd

- 10 multiple of one-quarter of the wave generated by the transmitter connected to the other two-wire line, said other shunt impedance circuit being located from the junction of said other two-conductor line with the main transmission line a distance equal to an odd multiple of one-quarter of the wave generated by the transmitter connected to said one two-conductor line, and means connected across said main transmission line between said junction and said antenna for matching the antenna to the characteristic impedance of the main transmission line for the different frequencies of said two transmitters.

4. In combination, a first source of high frequency energy of wavelength λ_1 , a second source of high frequency energy of longer wavelength λ_2 , a main line and a load connected to said main line, a first two-conductor line connecting said first source to said main line, a second two-conductor line connecting said second source to said main line, a first shunt circuit connected across said first two-conductor line at a distance located from the junction of said first line with said main line equal to

$$\frac{\lambda_2}{4}$$

35 said first shunt circuit comprising an inductance in parallel with a series circuit of inductance and capacitance, the values of said inductance and capacitance elements being such as to provide at 40 the terminals of the shunt circuit connected across said first two-conductor line a high impedance to the flow of energy from said first source and a low impedance to the flow of energy from said second source, a second shunt circuit connected across said second two-conductor line at a distance located from the junction of said second line with the main line equal to

$$\frac{\lambda_1}{4}$$

50 said second shunt circuit comprising a capacitance in parallel with a series circuit of inductance and capacitance, the values of the capacitance and inductance elements of said second shunt circuit being such as to provide at the terminals thereof a high impedance to the flow of energy from said second source and a low impedance to the flow of energy from said first source.

5. Apparatus in accordance with claim 4, characterized in this that the reactance values of the series connected inductance and capacitance elements of the first shunt circuit are made to be equal at the frequency of the energy of the second source, and the reactance values of the series connected inductance and capacitance elements of the second shunt circuit are made to be equal at the frequency of the energy of the first source.

6. In combination, a first source of high frequency energy having a narrow band of frequencies and a mean wavelength λ_1 , a second source of high frequency energy having a wider band of slightly lower frequencies and a mean wavelength λ_2 , a main line and a load connected to said main line, a first two-conductor line connecting said first source to said main line, a second two-con-

ductor line connecting said second source to said main line, a first shunt circuit connected across said first two-conductor line at a distance from the junction of said first line with the main line equal approximately to

$$\frac{\lambda_2}{4}$$

and a second shunt circuit connected across said second two-conductor line at a distance from the junction of said second line with the main line equal approximately to

$$\frac{\lambda_1}{4}$$

15 said first shunt circuit comprising a two-conductor line section open at one end and closed at the other and connected intermediate its ends to said first two-conductor line, the overall length of said first shunt circuit being approximately $\frac{3}{4} \lambda_1$, and the length of the shunt line section between the closed end and the intermediate point of connection to the first two-conductor line being 20 approximately

$$\frac{\lambda_2}{2}$$

15

20

25 said second shunt circuit comprising a first two-conductor line section and a second two-conductor line section, said last first line section having a length equal approximately to

$$\frac{\lambda_2}{4}$$

30

35 and being connected at one end to said second two-conductor line and at its other end to said second line section at a position intermediate the ends of said second line section, said second line section being open at one end and closed at the other end and having an overall length approximately equal to $\frac{3}{4} \lambda_1$, the distance between the closed end of said second line section and the 40 intermediate point of connection being approximately

$$\frac{\lambda_2}{2}$$

35

45 7. A system in accordance with claim 6, characterized in this that said first and second two-conductor lines, said main line, and said shunt circuits comprise concentric inner and outer conductors.

8. A system in accordance with claim 6, characterized in this that said first source has a frequency range between 51.98 and 52.02 megacycles and said second source has a frequency range between 48.25 and 51.25 megacycles, the mean or carrier frequencies of said sources being respectively 52 and 49.75 megacycles.

50 9. In combination, a first source of high frequency, a second source of high frequency energy of another and higher frequency, a common load circuit adapted to be energized simultaneously by both said sources, a connection from each source to said load circuit, and means individual to each connection, including a section of line three-quarters of a wavelength long at the frequency of said second source, for efficiently permitting the flow of energy in said connection from its associated source toward said load and for effectively preventing the flow of energy of the other frequency back toward said associated source, said connections from the sources to said load circuit, and said means, comprising concentric conductor lines.
